LAMP HOLDER

John E. Brock, Fairmont, and Dominick Zanotti, Morgantown, W. Va., assignors to Westinghouse Electric Corporation, East Pittsburgh, Pa., a corporation of Pennsylvania

Application October 26, 1951, Serial No. 253,432

3 Claims. (Cl. 226—20.4)

1

This invention relates to exhaust machines and the like and, more particularly, to a tubular lamp holder for an automatic exhaust machine.

In the automatic exhaust of tubular lamps, such as the "lumiline" lamp, each lamp is exhausted in a vertical position with the exhaust tubulation down. The "lumiline" lamp is a low-wattage linear light source, employed generally for showcase lighting, and having its filament extending the length of the lamp and connected at each end to a disc-base which requires a special type of base holder. One of the exhaust problems is to hold the lamp in a vertical position, securely centered with respect to the axis of the exhaust port, while it travels through an oven at elevated temperature.

One lamp holder now in use on an automatic machine for the exhaust of such a lamp comprises a spring-loaded set of jaws with the springs located below and outside of the baking oven of the exhaust machine. Reflected heat in the oven weakens the spring tension. Further by locating the springs outside the oven and distant from the gripping jaws the transmission of spring power is complicated. Another type of lamp holder now in use is a loose fitting guide ring within which the lamp rests and which does not hold and align the lamp securely in the desired vertical position.

Hence, it has been found advantageous, according to our invention, to provide a lamp holder having a weighted or gravitational clamping arrangement. Our lamp holder comprises a holder body, a lamp rest secured at each end of the body, and intermediate thereon, a gravitational slide block with a clamping arm attached to the upper portion thereof, slidable on the body and keyed to the body by a lower vertical slot and an upper inclined slot in the body. As the slide block falls downwardly by the force of gravity, the inclined slot in the block forces the upper portion of the block and the clamping arm backwardly against the lamp rests, thereby securely centering the tubular lamp in the vertical plane of the lamp rests during the exhaust cycle.

In its general aspect, our invention has the object of overcoming the afore-mentioned disadvantages of the prior art tubular lamp bulb holders for an exhaust machine and the like.

Another and specific object of our invention is the elimination of spring-loaded jaws and the loose-fitting guide rings of the conventional holders.

Another object is a tubular lamp holder having a weighted gravitational clamping arrange-

ment which securely centers the lamp in a vertical position.

A further object is a tubular lamp holder having a holder body, a lamp rest on each end of the body and a gravitational clamping device between said rests slidable on the body in a path predetermined by keying slots in said body.

Other objects and advantages will appear to those skilled in the art to which it appertains as the description thereof proceeds, both by direct recitation thereof and by implication from the context.

Referring to the accompanying drawing, in which like numerals of reference indicate similar parts throughout the several views.

Fig. 1 is a fragmentary plan view of the indexing table of an automatic exhaust machine embodying the tubular lamp holder of my invention;

Fig. 2 is a side elevation of our holder with a tubular lamp centered therein in the desired vertical position above the compression rubber assembly of a port of an automatic exhaust machine;

Fig. 3 is a sectional view of the holder and lamp on the line III—III of Fig. 2;

Fig. 4 is a sectional view of the holder and lamp on the line IV—IV of Fig. 2;

Fig. 5 is a sectional view of the holder and lamp on the line V—V of Fig. 2;

Fig. 6 is a sectional view of the holder and lamp on the line VI—VI of Fig. 2; and

Fig. 7 is a diagrammatic plan view of the automatic exhaust machine.

Referring now to the drawing in detail, and particularly to Fig. 1 and Fig. 2, an indexing table of a 24 port lumiline automatic exhaust machine 10 is designated by the reference numeral 12. Around the periphery of the table 12 is provided a series of ports 14, twenty-four in the present showing, circularly arranged in equi-spaced relationship. Adjacent each port 14, there is also provided a tubular lamp holder 16 of our invention, secured to the table 12, as hereinafter explained. Whereas the holders 16 are employed in the present embodiment on an automatic exhaust machine, it will be understood that the holders 16 can be used with any automatic sealing machine, basting machine, or seasoning machine for tubular lamps or electronic tubes. As shown particularly in Fig. 2, the portion of the table periphery about each port 14 and between successive holders 16 is generally hollow and forms a series of interconnected water jackets or cooling chambers 18 for cooling said ports 14. Above

55

the table 12 and extending circularly over 20 of the 24 ports is a tunnel-like oven 20.

Port

Each port 14 consists of a compression rubber assembly 21 and pinch clamp rubber assembly 22. Assembly 21 consists, as shown in Fig. 2, of an apertured exhaust rubber 23 mounted on a lower washer 24 in a hollow compression rubber body 25 to which is threaded on the upper end a cap 26 having a laterally extending lever or arm 28; an upper washer 30 on rubber 23; and ball bearings 32 between the cap 26 and washer 30. This cap 26 either presses washer 30 through ball bearings 32 against the exhaust rubber 23 to squeeze it about an exhaust tubulation 34 of a tubular lamp 36, thereby effecting an air-tight connection therewith, or releases the pressure on said rubber 23 to facilitate insertion or withdrawal of the tubulation 34 therefrom.

Extending below table 12, and threaded to the lower portion of body 25, is a hollow housing 38 of the pinch clamp rubber assembly 22. In addition to housing 38, assembly 22 comprises a cylindrical pinch-off rubber 40 within housing 38, and a bottom retaining plate 42 having a hole 44 in which an exhaust pipe or sweep 46 is secured.

Lamp holder body

This tubular lamp holder 16 of our invention comprises a holder body 48 (Fig. 2), an upper lamp rest 50 and a lower lamp rest 52 on said body, and a gravitational slide block 54 with a laterally extending clamping arm assembly 56 slidable on said body. The portion of a face 49 of this holder or plate-like body 48, adjacent the compression rubber assembly 41, slopes rearwardly to form bottom portion 57 of reduced width. A rod-like bottom extremity 58, projecting from said bottom portion 57, is cylindrical and of smaller diameter than the width of said bottom portion 57 and threaded for insertion into a hole 60 in the table 12, and for securement therein, as by means of a nut 62.

Above the sloping portion of the face 49, and centered near said face, a vertical lower slot 64, shown in Figs. 2 and 6 as having a length greater than the maximum desired travel of block 54, is cut through holder body 48. An inclined upper slot 66, shown in Figs. 2 and 4, sloping downwardly and away from face 49, approximately 15° from the vertical, is provided in the upper portion of body 48.

The holders 16 are securely centered in the desired vertical position, axially parallel to the axis of the ports 14, by a series of upper holder support brackets 68 (Figs. 1 and 2) of generally arcuate or curved configuration. The ends of adjacent brackets 68 overlap and are secured to the top of the body 48, as by means of screws 69 and 70. The width of brackets 68 is necessarily smaller as compared to the length to permit their passage with sufficient clearance through the oven 20.

Upper lamp rest

The adjustable upper lamp rest 50, shown particularly in Figs. 2 and 3, consists of two complementary vertical plates 72 and 74, each having shallow holder body slots 76 and 78 in their respective inner faces and symmetrical tapered or beveled edges 80 and 82 on one end diverging outwardly from said inner face for receiving a tubular lamp 36 therebetween. These plates 72 and 74 suitably longer than the width

of the holder body 48 are secured about said body in any desired location above slot 66 in body 48 by bolts 83 and 84, extending through the end portion of plates 72 and 74, and nuts 85 and 86.

Lower lamp rest

The adjustable lower lamp rest 52, shown in Fig. 2, suitably identical to upper lamp rest 50, consists of two plates, namely one plate 88 and another not shown, having slots and tapered edges respectively similar to slots 76 and 78 and edges 80 and 82. These plates are attached about body 48 in any desired location below slot 64 in body 48 by bolts 89 and 100 through the end portions of the respective plates.

It will be understood that upper lamp rest 50 may also serve as a stop complementary to slots 64 and 66 by limiting the upward motion of slide block 54 and that lower V-block 52 may operate in a similar manner to restrict the downward motion of said block 54.

Gravitational slide block

This gravitational slide block 54, as shown in Figs. 2, 4 and 5, consists of side plates 104 and 106 having tapered edges 108 and 110, respectively, similar in shape to edges 80, 82. In plate 104 below slot 66 are provided two threaded holes 111 and 112 for securing clamping arm assembly 56, as hereinafter described. A special bolt 113 (Figs. 2 and 4) having an unthreaded shank portion 114 and a threaded end portion 116 of smaller diameter than the shank portion 114, extends through a hole 118 in said plate 104, a roller 119 in the upper inclined slot 66, and a hole 120 in side plate 106. This roller 119 is carried on the shank portion 114 within the inclined slot 66. A nut 122 on threaded end portion 116 holds the side plate 106 against the adjacent end of the shank portion 114. By means of this shank portion 114 there is provided sufficient clearance between holder body 48 and side plates 104 and 106 to permit the desired gravitational sliding action of slide block 54.

Another special bolt 124 (Figs. 2 and 6), similar to bolt 113, having a shank portion 126 carrying a roller 127 and a threaded portion 128 extends through a hole 130 in the side plate 104, roller 127 in lower vertical slot 64, and a hole 132 in side plate 106. A nut 133 is provided on portion 128 for securing plate 106 to shank portion 126.

Clamping arm assembly

The clamping arm assembly 56, shown in Figs. 2 and 5, comprises a spacer plate 134 on the plate 104, a clamping arm or plate 136 on plate 134, and a laterally extending clamping finger 138 fitting a hole 139 in the outer extremity of the arm 136 and secured therein as by pinning. Arm 136, spacer 134 and plate 104 are secured together, as by bolts 140 and 142 extending through suitable holes in the arm 136, the spacer 134 and into the threaded holes 111 and 112 in side plate 104 of slide block 54. At the end of the sliding action of slide block 54 on body 48, finger 138, rod-like in shape, secures the lamp 36 in the edges 80 and 82 of upper lamp rest 50 and the corresponding edges of lower lamp rest 52 and axially aligns the lamp with port 14.

Operation

At station 1 of the automatic exhaust machine 10, shown in Fig. 7, the portion of the tubulation 34 of a last tipped off lamp 36 remaining in a compression rubber assembly 21 of a port 14 is

removed. Then the tubulation 34 of a lamp 36 to be exhausted is fitted in the exhaust rubber 23, being securely centered in holder 16, as herein-after explained, at station 2 or 3. At stations 4 to 23 the lamp is baked in oven 20 at approximately 350° C. The lamp is also pumped out in stations 4 and 5. A dry nitrogen gas flush is introduced at stations 6, 8, 10, 12 and 14. In the adjoining stations 7, 9, 11, 13 and 15 the gas is pumped out. The lamp is continuously pumped at stations 16 through 21 and given a final nitrogen fill at stations 22 and 23. Finally, at station 24 the lamp 36 is automatically tipped off and unloaded from the holder 16 by the exhaust operator.

In order to load a lamp 36 into a port 14 of machine 10, according to our invention, the exhaust machine operator first pushes the slide block 54 upwardly on holder body 48 with her left hand until the block hits upper lamp rest 50 or until bolt 113 hits the upper end of inclined slot 66 in body 48. With the block 54 in this position, the clamping finger 138 on arm 136 is moved outwardly sufficiently distant from the holder body 48 to permit insertion of the lamp 36, held in the operator's right hand, between the edges 80 and 82 of upper lamp rest 50, the similar edges of lower lamp rest 52 and the clamping finger 138, and to introduce a tubulation 34 of lamp 36 into the exhaust rubber 23 of compression rubber assembly 21. The operator now releases the gravitational slide block 54. The force of gravity moves the bolt 113 diagonally downward in the inclined slot 66 and the clamping finger 138 against lamp 136, thereby securely centering said lamp axially above the port 14 and against the edges of lamp rests 50 and 52 respectively. With her right hand the operator turns the lever 28, thereby compressing rubber 23 about tubulation 34 to effect an air-tight connection therewith.

Further, according to our invention, to unload the lamp 36 after tip-off at station 24, the operator merely lifts the lamp. This motion forces the bolt 113 upwardly in the inclined slot 66 and releases the gravitational force of block 54 on lamps 36, thereby permitting its easy removal from the holder 16.

Thus, it will be seen from the foregoing that our tubular lamp holder 16 has overcome the disadvantages of the prior art spring-loaded jaws and the loose-fitting guide rings of the conventional holders. Our holder 16 securely centers a tubular lamp 36 in the port 14 of the machine 10 and insures accurate loading and unloading of the lamps 36 from the machine 10.

Whereas a preferred embodiment of our invention has been disclosed, it will be understood that modifications may be made within the spirit and scope of the appended claims.

We claim:

1. A tubular lamp holder for an automatic

exhaust machine having a holder body, said body having a threaded lower extremity, a lower vertical slot and an inclined upper slot therethrough, a lamp rest secured about each end of the body, said lamp rests having two side plates each with an outwardly diverging edge on one end complementary to each other and a gravitational slide block slideable on said body, said block having two block side plates each with a side edge similar to said lamp rest edges, a bolt for slidably securing said block side plates about said body and extending through said block side plates a roller on said bolt and slideable in said upper inclined slot, a second bolt extending through said block side plate, a second roller on said second bolt and slideable in said lower vertical slot, and a clamping arm assembly secured to said block.

2. A tubular lamp holder for an automatic exhaust machine having a holder body, said body having a threaded lower extremity, a vertical lower slot and an inclined upper slot therethrough, a lamp rest secured about each end of the body, said lamp rest having two side plates each with an outwardly diverging edge on one end complementary to each other, and a gravitational slide block slideable on said body, said block having two block side plates each with a side edge similar to said lamp rest edges, a bolt for slidably securing said block side plates about said body and extending through said block side plates, a roller on said bolt and slideable in said inclined upper slot, a second bolt extending through said block side plates, a second roller slideable in said vertical lower slot, and a clamping arm assembly secured to said block, said clamping arm assembly comprising a spacer plate on one of said block side plates, a clamping arm on said spacer, and a laterally extending clamping finger on said arm.

3. An automatic exhaust machine having an indexing table, a series of exhaust ports arranged around the periphery of said table and a series of vertical gravitational tubular lamp holders adjacent and above said ports, each of said holders having a body secured to said table between said ports, a lamp rest secured about each end of said body and having lamp holder edges centered axially parallel to the axis of a port, a gravitational slide block slideable on said body and a clamping arm assembly on said body.
